DISPENSING CONTAINER

Filed March 11, 1931

UNITED STATES PATENT OFFICE

ALFRED J. CHAMBERLAIN, OF MILWAUKEE, WISCONSIN

DISPENSING CONTAINER

Application filed March 11, 1931. Serial No. 521,664.

This invention relates in general to containers and more particularly to a dispensing container.

One of the principal objects of the present invention is to provide a container of this character which is so constructed and organized as to facilitate the easy dispensing of the contents thereof into smaller receptacles or into other places while avoiding spilling of the contents being dispensed, the contents, even when the container is full, being delivered in a well defined stream which clears the edge of the container upon but a slight tipping or tilting of the container. Along with these advantages the container, when not actually used for dispensing its contents, provides a normal container structure entirely devoid of projections liable to be struck and damaged when the container is being shipped, handled or stored.

A further object of the invention is to provide a container having these advantages and capacities and which is of simple and durable construction, reliable and effective in operation and easy and comparatively inexpensive to manufacture.

In carrying out the present invention the container has its top provided with a portion inclining outwardly and downwardly toward the periphery of the container. An outlet opening is formed in the inclined portion and has organized therewith an outlet fitting equipped with spaced bearings in which a dispensing spout is slidably fitted. The bearings and the spout have a common axis which is located at right angles to the plane of the inclined portion. As a result the spout is inclined with respect to the major portion of the top and as it is slidably fitted in its bearings it may be pushed to retracted position, wherein it is located entirely within the confines of the container structure proper or it may be pulled out to projected or dispensing position wherein its discharge end overlies the periphery of the container thereby insuring the stream issuing from the discharge end clearing the edge or periphery of the container upon slight tipping thereof. This latter feature greatly facilitates accurate pouring of the contents into smaller re-

ceptacles or into other places and as this accurate pouring requires but slight tipping, handling of the container is facilitated and the container, if heavy, may be rested on its upper edge rather than upon the dispensing 55 spout. It will be understood that the dispensing spout is not as well adapted to take part in the support of the container as the relatively heavy and stronger part of the structure itself. The entire contents of the 60 container may be evenly and smoothly discharged without the contents becoming air bound at any time.

Other objects and advantages reside in certain novel features of the construction, arrangement and combination of parts which will be hereinafter more fully described and particularly pointed out in the appended claims, reference being had to the accompanying drawing forming a part of this specification, and in which:

Figure 1 is a perspective view showing a container embodying the present invention;

Figure 2 is an enlarged fragmentary view partly in transverse vertical section and partly in elevation and illustrating the upper portion of the container with which the dispensing means embodying the present invention is organized;

Figure 3 is a view similar to Figure 2 but 80 showing a different position of the dispensing spout;

Figure 4 is a fragmentary sectional view on an enlarged scale better illustrating the structure of the outlet fitting in which the dispensing spout is mounted; and

Figure 5 is a view in section taken on line 5—5 of Figure 2.

Referring to the drawing, the numeral 1 designates generally a container which may 90 be of any suitable type but which for the purpose of illustration is shown as being of the type usually employed for containing lubricating oil or the like. The body portion of the container is of conventional construction and has its upper end reduced as at 2 and suitably connected as by seam 3 with a depressed or cupped top 4.

The top 4 is provided with a portion 5 which is inclined downwardly and outward- 100

ly toward the periphery of the container. An outlet opening is provided in this inclined portion 5 and is equipped with an outlet fitting designated generally at 6 made up of two parts or sections designated at 7 and 8. The outer section 7 is provided at its outer end with a seat 9 and inwardly of the seat has a bearing portion 10 terminating in an inturned flange 11. The section 8 has a body portion 12 fitted within the inner end portion of the section 7 and the outer end of this body portion 12 has integral therewith an annular web or plate 13 carrying an integral bearing 14. The bearings 10 and 14 are coaxially arranged though longitudinally spaced. The two sections 7 and 8 are securely held assembled and are securely fastened to the inclined portion 5 of the top by a common seam structure designated generally at 15 and consisting of nesting angular flanges 15 and 16 formed on the sections 7 and 8, respectively, and interseamed or interfitted with an angular flange 17 formed integral with the margin of the outlet opening of the inclined part 5 of the top. It will be understood that the flanges 15, 16 and 17 are of angular form in cross section but, of course, extend angularly or for the full circumferential extent of the parts on which they are respectively formed.

In the spaced bearings 10 and 14 of the outlet fitting, a dispensing spout 20 is slidably fitted, the spout being constructed of a piece of seamed tubing and being a snug working and friction fit in the bearings 10 and 14. The ends of the spout 20 may be beaded over as indicated at 21 and 22 after assembly and the bead 22 may carry a finger grip 23 which facilitates manipulation of the dispensing spout or dispensing tube.

Due to the inclination of the part 5 and to the fact that the bearings of its outlet fitting have their axis extending at right angles to the inclined portion 5, the spout 20 is slidable along an axis inclined with respect to the plane of the main portion of the top whereby when the spout is pulled out to dispensing position as illustrated in Figures 1 and 3, its discharge end overlies or clears the adjacent portion of the periphery of the top or of the container. As a consequence, the stream that issues from the pouring spout has all portions beyond the container and the container does not have to be tipped excessively in order to have the stream clear its upper edge when the container is full or nearly so. On the contrary, the stream issuing from this inclined spout may be easily directed into smaller receptacles or into other places upon slight tipping of the container.

When the container is being shipped the spout is retracted as illustrated in Figure 2 and the container is closed by a conventional type of readily removable cap 25. Due to the fact that the spout is supported in spaced

bearings of the outlet fitting it will not tend to wobble or move in an uncontrolled manner during the dispensing operation. Further, as the spout is a snug friction fit in its bearings 10 and 14 it will remain in its extended position and the snug fit in the spaced bearings effectively precludes the escape of oil. If desired, in addition to the snug fit of the two bearings, packing 30 may be provided as an additional precaution against the uncontrolled escape or leakage of the contents of the receptacle during dispensing. This packing 30 is conveniently confined between flange 11 and plate 13 of the sections 7 and 8 of the outlet fitting. It is to be understood that the use of the packing 30 is optional and that it may be employed or not as desired.

When the container is being filled the spout 20 is pushed into its retracted position and in order to prevent the container from becoming air bound during filling, a venting groove 35 is provided in the outer portion of the spout by inwardly depressing the material thereof, this venting groove bridging the spaced bearings and the packing of the outlet fitting and permitting the outflow of air during the inflow of the liquid.

A handle 35 suitably connected to the main portion of the top facilitates handling of the container.

The organization thus described has the advantage of facilitating the dispensing of the contents of the receptacle in a well defined and controlled stream at all times and accomplishes this object upon slight tilting of the receptacle or container, when it is full or nearly so. Furthermore, the organization is such that the entire contents of the container or receptacle may be dispensed without the receptacle becoming air bound. When the container is being shipped or when it is being stored or at all times when its contents are not being dispensed, the dispensing spout is completely housed and protected by the container structure proper.

It is to be understood that the top, instead of being seamed to the body of the container may be in the form of a removable closure, as, for example, of the type and structure shown in my Patent No. 1,770,892, granted July 15, 1930.

The invention claimed is:

1. A container having a top provided with a portion inclining outwardly and downwardly toward the periphery of the container, an outlet fitting carried by said inclined portion and a short spout slidably fitted in said outlet fitting and having its discharge end overlying the edge of the upper portion of the container when the spout is pulled outwardly to its dispensing position, said spout having a diameter relatively great with respect to the length of the spout and being straight and free from bends throughout its length whereby to automatically vent the

container through said spout when discharging the contents of the container.

2. A container having a top provided with a portion inclining outwardly and downwardly toward the periphery of the container, an outlet fitting carried by said inclined portion and provided with spaced bearings, and a dispensing spout slidably and frictionally fitted in said spaced bearings, said spout having a diameter relatively great with respect to the length of the spout and being straight and free from bends throughout its length whereby to automatically vent the container through said spout when discharging the contents of the container.

3. A container having a top provided with a portion inclining outwardly and downwardly toward the periphery of the container, said inclined portion having an outlet opening, an outlet fitting for said opening comprising interfitted parts formed with spaced bearings, a common seam between said interfitted parts and the marginal wall of the outlet opening and a dispensing spout slidably fitted in the spaced bearings of said outlet fitting.

4. A container having a top provided with a portion inclining outwardly and downwardly toward the periphery of the container, an outlet fitting carried by said inclined portion and a dispensing spout snugly and slidably fitted in said outlet fitting, said dispensing spout having a venting groove bridging the outlet fitting in the inner position of the spout, said groove terminating short of the inner end of the spout whereby to secure an effective seal between the spout and the fitting in the dispensing position of the spout.

5. A container having a depressed part formed with a portion inclining outwardly and downwardly toward the periphery of the container, an outlet fitting carried by said inclined portion, a short dispensing spout slidably fitted in the outlet fitting and in its retracted position located entirely within the confines of the container structure while in its projected position, having its discharge end positioned to overlie the edge of the container, said dispensing spout having a straight opening free from bends extending therethrough, and a closure cooperable with said fitting for sealing the container when the spout is retracted.

In witness whereof, I hereto affix my signature.

55 ALFRED J. CHAMBERLAIN.
